US0D1016681S

(12) **United States Design Patent** (10) Patent No.: **US D1,016,681 S**
(45) Date of Patent: ** Mar. 5, 2024

(54) **HITCH PIN DEVICE**(71) Applicant: **Truck Shields, LLC**, Salt Lake City, UT (US)(72) Inventor: **Dennis H. Hancock**, Evanston, WY (US)(***) Term: **15 Years**(21) Appl. No.: **29/889,573**(22) Filed: **Apr. 13, 2023****Related U.S. Application Data**

(63) Continuation of application No. 29/815,765, filed on Nov. 16, 2021, now Pat. No. Des. 992,467, which is a continuation of application No. 17/132,808, filed on Dec. 23, 2020, now Pat. No. 11,766,904, which is a continuation of application No. 15/718,366, filed on Sep. 28, 2017, now Pat. No. 10,906,368, which is a continuation-in-part of application No. 15/418,442, filed on Jan. 27, 2017, now abandoned.

CLAIM

The ornamental design for a hitch pin device, as shown and described.

DESCRIPTION

FIG. 1 is a front and top perspective view of a hitch pin device showing my new design;

FIG. 2 is a front elevation view thereof;

FIG. 3 is a right side elevation view thereof;

FIG. 4 is a rear side elevation view thereof;

FIG. 5 is a left side elevation view thereof;

FIG. 6 is a top plan view thereof;

FIG. 7 is a bottom plan view thereof; and,

FIG. 8 is a rear and bottom perspective view thereof.

The broken dashed lines shown in the drawings are for illustrative purposes only and form no part of the claimed design. The broken dashed lines in the drawings depict unclaimed environmental subject matter.

The broken dash-dot-dash lines shown in the drawings indicate boundaries of the claimed design.
